US0D1024468S

(12) **United States Design Patent** (10) **Patent No.:** **US D1,024,468 S**
(45) **Date of Patent:** **** Apr. 23, 2024**

(54) **LAUNDRY DETERGENT HOLDER**

(71) Applicant: **Shenghui Wang**, Shenzhen (CN)

(72) Inventor: **Shenghui Wang**, Shenzhen (CN)

(**) Term: **15 Years**

(21) Appl. No.: **29/815,436**

(22) Filed: **Jan. 17, 2022**

(51) **LOC (14) Cl.** **15-05**

(52) **U.S. Cl.**

USPC **D32/25**

(58) **Field of Classification Search**

USPC D6/542-544; D23/213; D32/1, 6, 25,
D32/29.1

CPC B67D 1/124; B67D 1/1238; D06F 39/026

(57) **CLAIM**

I claim the ornamental design for a laundry detergent holder, as shown and described.

DESCRIPTION

FIG. 1 is a perspective view of the laundry detergent holder showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view of thereof; and,

FIG. 7 is a bottom plan view of thereof.

1 Claim, 7 Drawing Sheets
